UNITED STATES PATENT OFFICE.

DAVID McLAUGHLIN, OF DULUTH, MINNESOTA.

LOAD RETAINING OR RELEASING MEANS FOR VEHICLES.

SPECIFICATION forming part of Letters Patent No. 745,289, dated November 24, 1903.

Application filed July 18, 1903. Serial No. 166,136. (No model.)

To all whom it may concern:

Be it known that I, DAVID McLAUGHLIN, a citizen of the United States, residing at Duluth, in the county of St. Louis and State of Minnesota, have invented certain new and useful Improvements in Load Retaining or Releasing Means for Vehicles; and I do hereby declare the following to be a full, clear, and exact description of the invention, such as will enable others skilled in the art to which it appertains to make and use the same.

My invention relates to position-governing means for load-retaining stakes, and has for its object the provision of stake-retaining means which may be easily released by an operator in a position of safety.

With this and other objects in view it consists, in combination with a suitable load-supporting structure, of a load-retaining stake pivoted thereto, a bracket secured to said structure, means supported by said bracket for securing one end of a stake-controlling chain, a stake-controlling chain, and operating means for governing said securing means.

It also comprises certain other constructions, combinations, and arrangements of parts, as will be hereinafter described and claimed.

In the drawings, Figure 1 is a perspective view of a portion of a logging-car of the Russell type, showing my invention mounted thereon. Fig. 2 is a detail perspective view, on an enlarged scale, of a chain-anchoring bracket and means supported thereby forming part of my said invention. Fig. 3 is a plan view, on an enlarged scale, of a portion of said supporting structure and of portions of said invention mounted thereon.

In the drawings, 1 is a transverse bolster forming part of a logging-car, upon the side of which bolster, near the end thereof, is pivoted a stake 2, to which stake intermediate of its ends is secured an anchor-chain 3. To the same side of said bolster in rear of said stake is secured a bracket 4, having a downwardly-directed tooth 5 formed thereon. Pivoted near its upper end to an elbow 6, forming part of said bracket, is a lever 7, provided above its pivotal point with an upwardly-directed tooth 8, adapted in co-operation with said tooth 5 to engage said

anchor-chain in rear of said stake. Said lever is adapted to swing in the same plane with said stake and is provided at its lower end with a foot directed forwardly and rearwardly in said plane, the rearward end of which foot is preferably provided with a counterbalance-weight 9, and the forward end of which foot is adapted in operative position to engage a lip 11, formed upon a collar 12, which collar is secured in any suitable manner to a shaft 13, projected through said bracket at right angles to the plane within which said lever swings. A button 14 is pivoted to the face of said tooth 5 and is adapted in operative position to extend downwardly across the space between the tooth 5 and the tooth 8 to prevent said chain from slipping laterally out of engagement with said teeth. The shaft 13 preferably extends to the end of said car and is provided at such place with an operating-handle 15. Said shaft may be secured against revolution by any suitable means, as by a chain 16, adapted at one end to removably engage said handle and at the opposite end secured to the frame of said car. Upon the upper face of said bolster I preferably pivot a dog 17, the nose of which is adapted in operative position to swing horizontally into the backward path of said stake to prevent the accidental rearward fall of the same before the load is in position to do so. The tail of said dog is adapted in operative position to bear against the edge of a sill 18, extending longitudinally of said bolster, whereby the movement of said dog is limited.

I am aware that load retaining and releasing means similar in some respects to my said invention has heretofore been used, and notably the means illustrated and described in my application, filed on the 2d day of December, 1903, Serial No. 133,589, for patent for load retaining and releasing means for vehicles; but I have found that such previous means do not sufficiently provide for the stretching of the stake-retaining chain, and when such stretching occurs the chain has to be shortened by removing a link or by other comparatively laborious means. In my present invention the construction of the tooth 5 and the tooth 8 and adjoining parts is such as to permit the operative portion of the chain to be shortened or extended by merely giving

the chain a quarter-turn and inserting one or another of the links between said teeth.

Having now described my invention, what I claim, and desire to secure by Letters Patent, 5 is—

1. In load retaining and releasing means, the combination with a load-supporting structure provided with a load-retaining stake pivotally secured thereto and a chain secured at 10 one end to said stake, of a bracket secured to said structure in rear of said stake and provided with a downwardly - directed tooth formed thereon, a lever pivotally secured to said bracket and adapted to swing in the same 15 plane as said stake and provided above its pivotal point with an upwardly-directed tooth registering with the tooth formed on said bracket and adapted in coöperation with the first said tooth to grip said chain, and provided below its pivotal point with a foot terminating at one end in a hook, means for engaging said hook to secure said lever in operating position, and means for controlling said engaging means, substantially as described.
2. In means for the purposes described, the 20 combination with a load-supporting structure of a chain or cable engaging anchorage comprising a bracket secured to said structure provided with a downwardly-directed tooth,

30 a lever pivoted to said bracket and provided above its pivotal point with an upwardly-directed tooth adapted in coöperation with said downwardly-directed tooth to grip a chain or cable, said lever being provided below its pivotal point with a foot having a hook formed 35 upon one end, means for engaging said hook to secure said lever in operative position, and means for controlling said engaging means, substantially as described.

3. In means for the purpose described, the 40 combination with a load-supporting structure of a chain or cable engaging anchorage comprising a bracket secured to said structure and provided with a downwardly - directed tooth, a lever pivoted to said bracket and provided above its pivotal point with an upwardly-directed tooth adapted in coöperation with said downwardly-directed tooth to grip a chain or cable, and means for securing said lever in operative position, substantially as 45 described.

In testimony whereof I hereunto affix my signature in presence of two witnesses.

DAVID McLAUGHLIN.
